CHICKEN BROODER

Charles L. Murray, Waco, Tex.

Application February 19, 1943, Serial No. 476,443

2 Claims. (Cl. 119—33)

This invention relates to chicken brooders, and the primary object of the present invention is to provide a device of this kind which is comparatively simple in construction, highly efficient for the intended use, and easy to maintain and operate.

Specific objects and features of the invention will become apparent from the following description when considered in connection with the accompanying drawings, and the invention consists in the novel form, combination and arrangement of parts hereinafter more fully described, shown in the accompanying drawings and claimed.

In the drawings:

Figure 1 is a top plan view, partly broken away and in section, of a brooder constructed in accordance with the present invention.

Figure 2 is a front elevational view thereof.

Figure 3 is a substantially central longitudinal sectional view of the same, taken on line 3—3

20 of Figure 1; and

Figure 4 is a substantially central transverse sectional view of the same, taken on line 4—4 of Figure 1; and

Figure 5 is a wiring diagram showing the arrangement of the heating and associated elements in an electrical circuit.

Referring in detail to the drawings, the present brooder includes a horizontal elongated rectangular base frame 5 provided with corner supporting legs 6. The bottom of the frame 5 is closed by means of a depending pan-shaped member 7 which is closed at the top by a flat wall 8 having a series of warm air outlet openings along the sides and ends of the same as at 9. Movable through the front wall of the frame 5 and slidably mounted on guide rails R above the cover plate or wall 8 are drawer-like dropping pans 10 whose outer side and end walls are located inwardly of the openings 9 as shown clearly in Figures 3 and 4. Thus, the pans 10, which are provided at the front with knobs or handles 11, may be readily removed for disposal of the droppings in an obvious manner.

Disposed upon the base frame 5 is a rectangular casing 12 having side and end walls 12a and 12b whose lower edges terminate above the base frame 5 to provide passages as at 13. Mounted or built suitably on the casing 12 at the sides are feed boxes 14 from which the feed may flow by gravity through the passages 13 to the interior of the casing 12 for access by the chicks within said casing. Similarly, water troughs 15 are mounted at the ends of casing 12 from which water may pass by gravity through the passages 13 to the

interior of casing 12 for access by the chicks within said casing. The bottom of the casing 12 is provided with a foraminous floor 16 which is preferably composed of suitable wire mesh fabric through which the droppings may pass into the dropping pans 10. As the feed boxes and watering troughs are of conventional design, specific description thereof is unnecessary. The casing 12 is divided longitudinally into two compartments by means of a partial partition 17 depending from the top of the casing 12 and a vertically slotted fabric curtain 18 depending from said partition to a point in proximity to the floor 16. One compartment is covered by glass panels 19, while the top of the other compartment may be left open. In warm weather, the chicks may safely pass into the open compartment, while they may seek refuge within the compartment, which is covered by the glass panels 19, for warmth. Both compartments may receive heated air from the chamber defined within the pan shaped member 7 and its cover 8, which air passes through the warm air escape openings 9 upwardly into the casing 12. Said air may be heated by means of suitable heating elements such as heating lamps 20 disposed in a longitudinal series within the chamber defined by member 7 and its cover 8 upon a suitable support as at 21. The member 7 may have a suitably located inlet for admittance of outside air to be heated by lamps 20. These heating elements may be placed in parallel in a heating circuit as shown in Figure 5, and a pilot lamp 22 may also be provided in this circuit in parallel with the heating elements or lamps 20 as is also shown in Figure 5, said pilot lamp being suitably mounted where desired, such as at the top of the partition 17 where it may be readily seen so as to note when the heating lamps are in operation. Also included in this heating circuit is a thermostat 23 which controls the operation of the heating elements or lamps 20 and may be suitably mounted in the heating chamber defined by the member 7 and its cover 8. By this means, the temperature within the closed covered chamber located beneath the panels 19, may be automatically regulated. Current may be supplied to the heating circuit by means of a suitable attachment cord 24, one end of which may be plugged into a receptacle 25 provided at the front of the brooder, the other end of the attachment cord being adapted to be plugged into any ordinary house outlet receptacle for deriving current from a so-called house wiring system.

In use, the chicks will be placed in the brooder upon the floor 16, and by placing the elements 20

in operation, the chambers of the casing 12 may be supplied with warm air, the chamber beneath the glass panels 19 being kept the warmer by the confinement of most of the warm air therein. Droppings may be forced through the foraminous floor 16 when they do not naturally fall therethrough, and these droppings, which are received by the dropping pans 10, may be readily disposed of by removal of the drawers of which the dropping pans form parts. The supply of water and feed to the troughs 15 and boxes 14 may be readily replenished from time to time as found necessary, reserve supply feed bottles B being provided for supplying water to the troughs 15 by the barometric principle.

From the foregoing description, it will be seen that I have provided a chicken brooder which is well adapted for carrying out the stated objects of the invention.

What I claim as new is:

1. A chicken brooder comprising a horizontal rectangular base frame provided with corner supporting legs, a pan shaped member closing the bottom of said base frame and provided with a flat top wall so as to define a heating chamber, said top wall having marginal warm air escape openings, a drawer embodying a dropping pan removably slidably mounted in the base frame above said cover for the heating chamber, a casing mounted on the base frame and having end and side walls terminating above the bottom of said casing to form passages, feed boxes and

water troughs mounted respectively on the sides and end of said casing and arranged for the passage of feed and water therefrom inwardly through said passages, and heating means within the heating chamber, said casing having a foraminous floor through which droppings may pass to the dropping pan.

5 2. A chicken brooder comprising a horizontal rectangular base frame provided with corner supporting legs, a pan shaped member closing the bottom of said base frame and provided with a flat top wall so as to define a heating chamber, said top wall having marginal warm air escape openings, a drawer embodying a dropping pan removably slidably mounted in the base frame above said cover for the heating chamber, a casing mounted on the base frame and having end and side walls terminating above the bottom of said casing to form passages, a foraminous 10 15 20 25 30 floor for the casing above said drawer, feed boxes and water troughs mounted respectively on the sides and end of said casing and arranged for the passage of feed and water therefrom inwardly through said passages, and heating means within the heating chamber, said casing being divided into two compartments by means of a longitudinal partial partition and a cloth vertically slitted curtain depending from said partition, one of said compartments having the top thereof covered by glass panels.

CHARLES L. MURRAY.
